(57) CLAIM

The ornamental design for a onesie, as shown and described.

DESCRIPTION

FIG. 1 shows a top and side perspective view of a onesie.

FIG. 2 shows a left side elevation view thereof.

FIG. 3 shows a right side elevation view thereof.

FIG. 4 shows a top plan view thereof.

FIG. 5 shows a bottom plan view thereof; and,

FIG. 6 shows a top and side perspective view in a closed version thereof.

The even dash broken lines illustrating a onesie represent portions of the onesie that forms no part of the claimed design.

The uneven dash broken lines adjacent to the shaded area represent boundaries that form no part of the claim.

The even dash broken lines within the bounds of the design represent stitching that forms no part of the claim.

1 Claim, 4 Drawing Sheets
